UNITED STATES PATENT OFFICE.

WILFRID HARTLEY, OF UTICA, AND EUGENE D. RIVERS AND EDWARD BEACH, OF ILION, NEW YORK, ASSIGNEES TO REMINGTON ARMS COMPANY, OF ILION, NEW YORK.

FIREARM.

SPECIFICATION forming part of Letters Patent No. 705,234, dated July 22, 1902.

Application filed September 20, 1901. Serial No. 76,856. (No model.)

To all whom it may concern:

Be it known that we, WILFRID HARTLEY, of Utica, in the county of Oneida, and EUGENE D. RIVERS and EDWARD BEACH, of Ilion, in the county of Herkimer, State of New York, have invented certain new and useful Improvements in Firearms; and we do hereby declare that the following is a full, clear, and exact description of the invention, which will enable others skilled in the art to which it appertains to make and use the same, reference being had to the accompanying drawings, and to the letters and figures of reference marked thereon, which form part of this specification.

The object of our invention is to provide a firearm that is simple and cheaply constructed and with a minimum number of parts, that is capable of being easily taken apart, and is convenient and efficient in operation.

In the drawings, Figure 1 shows a partial longitudinal section and a partial side elevation, with one of the side plates removed, of the frame and operative parts of the firearm. Fig. 2 shows a cross-section taken on the line of the securing-bolt. Fig. 3 is a section of the barrel close to the rear end.

Referring to the reference characters in a more particular description, 1 indicates the barrel, which is provided on the under side at and adjacent to the rear end with grooves *a a*. These grooves are adapted to receive the upper edges of the sheet-metal side plates 2 of the frame. The frame consists of the said side plates and a middle skeleton-frame piece 3 of an irregular form and including also the trigger-guard, and all secured together by rivets *b b*. On the under side of the barrel a little forward of the rear end is secured, preferably by a dovetailed joint, as shown, the barrel-retaining lug 4, which fits as to its front and rear sides into a notch or recess in the frame part 3 and as to its right and left sides between side plates 2. The thumb-screw 5 passes up from the under side

of the frame and engages with the retaining-lug 4 and when tightened firmly secures the barrel to the frame.

The fore stock 18, which is secured to the barrel, is provided with a tenon 18^a, which enters the opening between the side plates 2 at the front end of the frame. The barrel may be readily separated from the frame by loosening the screw 5, when the retaining projection 4 draws out of its socket in the direction of the length of the screw and the tenon 18^a of the fore stock draws out in the same direction. It may be noted at this point that the arrangement of the grooves *a a* in the under side of the barrel, engaging with the side plates of the frame for a considerable extent lengthwise, serves to hold the frame and barrel in perfect alinement, and the same, together with the retaining-lug, engaging in the socket in the frame, serves when the screw 5 is tightened to unite the parts practically as one piece. The rear stock 19 is secured to the frame by a bolt 20, which engages in a screw-threaded opening in the rear end of the intermediate frame part 3.

What we claim as new, and desire to secure by Letters Patent, is—

1. The combination in a firearm of the barrel portion having grooves in its under side, a frame having side plates engaging in said grooves and means for securing the barrel portion and frame together, substantially as set forth.

2. The combination in a take-down firearm of the barrel having grooves in its under side and a depending lug or projection of a frame having side plates, the upper edges of which are received in said grooves, and having a recess to receive said lug or projection and means for securing the barrel and frame together, substantially as set forth.

3. A frame construction for a firearm consisting of the sheet-metal side plates and an intermediate skeleton-frame part including the trigger-guard and rivets passing trans-

versely through the said side plates and skeleton frame securing them together, substantially as set forth.

4. A frame construction for a firearm consisting of the sheet-metal side plates, an intermediate skeleton-frame part and rivets passing through the said side plates and skeleton plates securing them together, substantially as set forth.

In witness whereof we have affixed our signatures, in presence of two witnesses, this 4th day of September, 1901.

WILFRID HARTLEY.
EUGENE D. RIVERS.
EDWARD BEACH.
